(52) U.S. Cl.

The ornamental design for a tapered box, as shown and
described.USPC **D9/431**; D9/432; D9/433

DESCRIPTION

(58) **Field of Classification Search**FIG. 1 is a front, top, and left perspective view of the tapered
box shown in an assembled state showing my new design.
FIG. 2 is a top plan view thereof.USPC D9/414-434, 442-445, 456, 457, 542,
D9/563, 600, 614-624, 655, 657, 658,
D9/661, 685, 695, 697-699, 707, 708,
D9/711, 754, 759, 772-776; D3/273,
D3/276, 304, 305, 307, 309-313;
D7/601, 602, 709; D19/75, 90

FIG. 3 is a bottom plan view thereof.

CPC B65D 5/00; B65D 5/001; B65D 5/0015;
B65D 5/0227-5/0254; B65D 5/18; B65D
5/6605; B65D 5/48024; B65B 5/06

FIG. 4 is a front elevational view thereof.

See application file for complete search history.

FIG. 5 is a rear elevational view thereof.
